J. R. ALEXANDER

RAILROAD SIGNALING MECHANISM

Filed Dec. 3, 1921

2 Sheets-Sheet 2

UNITED STATES PATENT OFFICE.

JOHN R. ALEXANDER, OF NEW ALBANY, INDIANA, ASSIGNEE OF ONE-THIRD TO
THOMAS ALEXANDER, OF TOLEDO, OHIO.

RAILROAD SIGNALING MECHANISM.

Application filed December 3, 1921. Serial No. 519,620.

To all whom it may concern:

Be it known that I, JOHN R. ALEXANDER, a citizen of the United States, residing at New Albany, in the county of Floyd and State of Indiana, have invented certain new and useful Improvements in Railroad Signaling Mechanism, of which the following is a specification, reference being had to the accompanying drawings.

10 This invention relates to certain improvements in railroad signaling mechanism and has relation more particularly to a mechanism of this general character of a train-operated character, and it is an object of 15 the invention to provide a novel and improved mechanism wherein a warning signal is adapted to operate at desired locations along the trackway and also wherein a gate at a railroad crossing or the like is 20 automatically caused to lower and raise.

Another object of the invention is to provide a novel and improved mechanism of this general character embodying both an audible and visual signal so that the 25 vice may operate with equal facility either in the daytime or after nightfall.

An additional object of the invention is to provide a novel and improved mechanism of this general character wherein a gate is 30 caused to automatically lower at a crossing or the like in advance of the arrival of a train at such location and wherein signaling means is caused to operate under control of the approaching train before the gate 35 is lowered.

The invention consists in the details of construction and in the combination and arrangement of the several parts of my improved railroad signaling mechanism whereby 40 certain important advantages are attained and the device rendered simpler, less expensive and otherwise more convenient and advantageous for use, as will be herein-after more fully set forth.

45 The novel features of my invention will hereinafter be definitely claimed.

In order that my invention may be the better understood, I will now proceed to describe the same with reference to the accompanying drawings, wherein:

Figure 1 is a view in top plan and of a diagrammatic character illustrating a signaling mechanism constructed in accordance with an embodiment of my invention;

50 Figure 2 is an enlarged fragmentary view

partly in section and partly in top plan illustrating a frog as herein embodied, together with certain of the parts associated therewith;

Figure 3 is a sectional view taken substantially on the line 3-3 of Figure 1 and on an enlarged scale;

Figure 4 is a fragmentary view partly in elevation and partly in section illustrating the means as herein disclosed for maintaining a gate in lowered position;

Figure 5 is an elevational view of a gate in raised position and the parts concomitant to said gate;

Figure 6 is an enlarged fragmentary view partly in section and partly in elevation illustrating the means for cushioning the downward movement of a gate and effecting its upward movement; and

Figure 7 is an elevational view of one of the columns or standards arranged remote from a signaling station or gate.

As disclosed in Figure 1 of the drawings, C denotes a crossing or other station at which are arranged signaling means and gates constructed in accordance with an embodiment of my invention. As the structure at all of the crossings or similar stations is of corresponding construction and operate in the same manner, it is believed that the invention as illustrated in the accompanying drawings is sufficient for the present disclosure. While in Figure 1 the gates, generally indicated at G, are arranged at only one side of the trackway, it is to be understood that the same can be arranged at both sides of the trackway by duplicating the structure as herein disclosed.

Each of the gates G, as particularly illustrated in Figure 5, is normally in a raised or vertically disposed position and comprises an elongated member 1 provided at its lower or supported end portion with a weighted extension or tail piece 2. The gate G is supported for swinging movement by a horizontally disposed shaft 3 having each end portion engaged with a cross member 4 connecting the upper end portions of the vertically disposed members 5 of the supporting frame for the gate G.

Each of the members 4 is provided with an internal chamber 6 in which is arranged a coil spring 7 of requisite tension, said spring surrounding the shaft 3 and having one end portion secured thereto while the opposite

end portion of the spring 7 is secured to a wall of the chamber 6. As the gate G moves downwardly, the spring 7 serves to cushion such downward movement and also places the 5 spring 7 under such tension to facilitate the upward or raising movement of the gate G.

The weighted portion 2 serves as a counterbalance for the gate G and to further assure such counterbalance, the portion 10 2 of the gate is provided with the weighted members 8.

Pivottally engaged with the outer end portion of the member 1 of the gate G is an extension rod 9 and adapted to have engaged 15 at its free extremity a signal 10 herein disclosed as a lamp. A lamp is particularly adapted for use after nightfall and it is to be understood that in the daytime a flag is intended to be substituted for the lamp.

20 Pivottally engaged with the member 1 inwardly of its outer end, as at 11, is a brace member or rod 12 having sliding connection, as at 14, with the rod 9 so that when the gate G is in its raised position, the downward movement of the rod 9 is limited. This brace member also serves, as the gate is lowered, to cause the extension or rod 9 to assume a position substantially in longitudinal alinement with the member 1.

30 When the gate G is in its lowered position, the ground rests 15 engage the roadway or other surface whereby the gate is further supported in desired position when lowered.

35 Pivottally engaged, as at 16, with the upper extremity of one of the members 5 is a sidewalk gate 17 which raises and lowers with the gate G. The pivoted end portion of the gate 17 is provided with a tail extension 18 which is operatively connected 40 through the medium of the link 19 with the gate G above the shaft 3. By this arrangement, the gate 17 is properly operated from the gate G in its movements.

45 The supporting structure for the gate G is mounted upon a base 20 of cement or other material and also secured to said base 20 is an upstanding column or pole 21, said column or pole 21 being also secured to the 50 supporting structure for the gate by the clamping arms 22.

The column or pole 21 is of length to extend to a desired altitude and is provided at its upper portion with a cross member 23 disposed in the same general direction as the 55 adjacent trackway and associated in a conventional manner with the cross member 23 and the column or pole 21 are the bracing arms 24.

60 Pivottally engaged, as at 25, with the column or pole 21 at a desired height or altitude is the arm 26 of the semaphore 27. Depending from the semaphore 27 through the instrumentality of the coil spring 28 or 65 its equivalent is a lamp 29. The lamp 29 is

particularly adapted for use after nightfall as during the daytime the semaphore 27 is sufficient to provide the desired visual signal.

The pivoted extremity of the arm 26 is provided with an extension 30, said extension 70 30 being in continuation of and preferably coplanar with the arm 26. Operatively engaged with the free end portion of the extension 30 is an upstanding rod 31 coupled by the turnbuckle 32 or the like with the 75 second rod 33.

The upper portion of the rod 33 is pivotally engaged with an end portion of a lower arm 34 comprised in a rock member M, said rock member being preferably substantially 80 X-shaped. The member M at its center is engaged, as at 35, with the column or pole 21 at a predetermined point above the pivotal connection 25 of the semaphore arm 26.

The second lower arm 34' of the member 85 M is operatively engaged with a resilient member 35' secured to and extending laterally from the column or pole 21. The outer or free end portion of the resilient member 35' is provided with a fork or yoke 36 90 between which is arranged and supported a helical spring 37 to which is secured a bell B preferably of a clapper type.

Secured to the gate G above the shaft 3 is a flexible member 38, preferably a chain 95 embodying twisted links. The member 38 passes over suitably positioned guide pulleys 39 and leads to and is connected with a rod 40 positioned between the rails 41 of the trackway and extending longitudinally 100 of said trackway. Interposed in the member 38 is a turnbuckle 42 so that said member may be maintained taut. The rod 40 also preferably comprises sections connected by a turnbuckle 43 to further maintain the 105 desired tautness.

The rod 40 is operatively engaged with an arm of a bell crank lever 44 mounted upon a support 45 for swinging movement in a horizontal direction, said support being also 110 preferably positioned between the rails 41. The free end portion of the second arm of the bell crank lever 44 has operatively engaged therewith a link 46 which is also operatively engaged with the free end portion 115 of a beam 47. The end portion of the beam 47 remote from the link 46 is pivotally engaged with a support 48 whereby said beam has swinging movement in a horizontal direction.

120 Operatively engaged with the central portion of the beam 47 is an arm 49 substantially perpendicular thereto and which is disposed toward a rail 41. The extremity of the arm 49 immediately adjacent the rail 41 is provided with a frog 50 which is constantly urged toward the rail and normally maintained in contact therewith through the instrumentality of an expandible member or coil spring 51. The frog 50 is arcuate in 125 130

form and as a train passes thereover the flange of a wheel of the locomotive or other rolling stock passes between the head of the rail 41 and the frog 50 and forces said frog 5 away from the coacting rail, which movement results in a rocking of the beam 47 and desired movement of the bell crank lever 44, causing pull to be imposed upon the rod 40 whereby the gate G with which 10 said rod 40 is operatively engaged is caused to move downwardly. As the beam 47 is swung under the influence of the flange of a wheel, the same passes beneath and is engaged by a vertically swinging latch 52 15 whereby the gate is held in its lowered or closed position until the latch 52 is released from the beam 47.

A frog 50 is associated with each of the gates G and at a sufficient distance in advance thereof so that it will be assured that a gate G will be lowered at a suitable time in advance of the train reaching the crossing C and by providing two gates G each independently operated, it is assured that a gate G will be lowered irrespective of the direction in which the train may be traveling upon the trackway.

The latch member 52 is pivotally supported, as at 53, by a supporting standard 54 positioned between the rails 41 and in relatively close proximity to the beam 47. The pivoted end portion of the latch member 52 is provided with a tail piece 55 with which is engaged a pair of flexible members 56 or chains 56. Each of these chains 56 is disposed over suitable guide rollers 57 and is operatively engaged with a horizontally swinging beam 58. Each of the beams 58 is positioned a suitable distance at opposite sides of a frog 50 and is provided intermediate its ends with an outstanding rod 59 having a frog 60 which is normally maintained in contact with the second rail 41 of the trackway.

Upon inward movement of either of the frogs 60, the beam 58 will be swung in a direction to impose sufficient pull upon the latch member 52 to release the same from the coacting beam 47 so that the associated gate G will be permitted to assume a raised or upright position. Each of the frogs 60 is normally maintained in contact with its associated rail by an expansible member or coil spring 61.

In the present embodiment of my invention, the semaphore 27 and the bell B are associated with only one of the gate structures and operatively engaged with each of the upper arms 62 of the member M is a flexible member or chain 63 which extends upwardly in contact with the suitably positioned guide rollers 64 and is engaged with a rod 65, the rod 65 adjacent the post or column 21 being also operatively engaged with a guide pulley 66.

The rods 65 at each side of the post or column 21 are arranged in series with adjacent rods connected by a flexible member 67 so that each of the rods may have a slight independent movement as the occasions of practice may require. Certain of the rods 65 are supported for sliding movement by guide pulleys 68 depending from a cross member 69 carried by a post or column 70 positioned at a desired location along the trackway. The rod 65 supported by each of the cross beams 69 has operatively engaged therewith a flexible member 70 passing over a suitably positioned guide roller 71 and secured to a vertically disposed rod 72 arranged in close proximity to the post or column 70.

The rod 72 preferably comprises sections connected by a turnbuckle 73 to assure the desired tautness. The lower end portion of the rod 72 has secured thereto a flexible member or chain 74 which passes under a suitably located guide roller 75 and is operatively engaged with a horizontally swinging beam 76 positioned between the rails 41 of the trackway. The beam 76 has operatively engaged therewith a rod 77 terminating in a frog 78 normally in contact with a rail 41 and maintained in said contact by a coil spring 79.

As the flanges of the wheels of the train force the frog 78 inwardly, the member M is rocked, resulting in a vibration of the resilient member 35' and of the semaphore 27 so that both a visual signal and an audible signal is given of the approach of a train. The wheels of the train intermittently force a frog 78 inwardly, whereby the requisite ringing of the bell B is assured and the vibration of the semaphore 27 maintained. Associated with the semaphore 27 is a spring 27' which operates imparting swinging movement to the semaphore independently of the train actuated members whereby the desired vibration of the semaphore 27 is assured.

In Figures 2 and 3, I have illustrated in detail the structure concomitant to a frog 78 but it is to be understood that a similar structure is employed in connection with the frogs 50 and 60. As illustrated in Figures 2 and 3, the frog proper has movement in the slots 80 provided in an end portion of a casing 81 and also with an extension 82 disposed within said casing and with which a rod 77 is directly connected. The expansible member or spring 79 encircles the rod 77 and is interposed between the outer closed end of the casing 81 and the shoulder 83 provided by the inner or inserted end of the extension 82.

From the foregoing description it is thought to be obvious that a railroad signaling mechanism constructed in accordance with my invention is particularly well

adapted for use by reason of the convenience and facility with which it may be assembled and operated, and it will also be obvious that my invention is susceptible of some 5 change and modification without departing from the principles and spirit thereof and for this reason I do not wish to be understood as limiting myself to the precise arrangement and formation of the several 10 parts herein shown in carrying out my invention in practice except as hereinafter claimed.

I claim:

- 15 1. In a train signaling mechanism, a support, a semaphore pivotally engaged with said support, the pivoted portion of the semaphore being provided with an extension, a substantially X-shaped rock member engaged with the support, a rod operatively connecting one of the arms of the rock member and the extension of the semaphore, an audible signal supported for vibration, an operative connection between a second arm of the rock member and the audible signal, and train actuated means operatively engaged with each of the remaining arms of the rock member to impart movement to the rock member for vibrating the semaphore and the audible signal.
- 20 2. In a train signaling mechanism, a support, a semaphore pivotally engaged with said support, a substantially X-shaped rock

member engaged with the support, a rod operatively connecting one of the arms of the rock member and the semaphore, an audible signal supported for vibration, an operative connection between a second arm of the rock member and the audible signal, train actuated means operatively engaged with each of the remaining arms of the 35 rock member imparting movement to the rock member for vibrating the semaphore and the audible signal, and a spring associated with the semaphore imparting swinging movement thereto in one direction independently of the train actuated means.

3. In a train signaling mechanism, a support, a semaphore pivotally engaged with said support, a substantially X-shaped rock member engaged with the support, a rod 50 operatively connecting one of the arms of the rock member and the semaphore, an audible signal supported for vibration, an operative connection between a second arm of the rock member and the audible signal, and train actuated means operatively engaged with each of the remaining arms of the 55 rock member to impart movement to the rock member for vibrating the semaphore and the audible signal.

In testimony whereof I hereunto affix my signature.

JOHN R. ALEXANDER.
